INVENTOR

BY ATTORNEY

UNITED STATES PATENT OFFICE.

REGINALD F. LANDRUM, OF BROOKLYN, NEW YORK.

CONNECTER.

Application filed January 29, 1925. Serial No. 5,486.

To all whom it may concern:

Be it known that I, REGINALD F. LANDRUM, a citizen of the United States, residing at Brooklyn, in the county of Kings and 5 State of New York, have invented certain new and useful Improvements in Connecters, of which the following is a specification.

This invention relates to improvements in 10 buckles, and has for its object the provision of a hollow belt buckle which will serve both as a waterproof container for articles of convenience and will also function efficiently as an ordinary belt buckle.

15 It has long been a desideratum among bathers to have a device for holding keys, cigarettes or toilet articles out of contact with the water and which at the same time may be worn while in the water without 20 interfering with bathing or swimming. To accomplish this object hitherto, devices have been made as waterproof containers for keys, cigarettes, money and toilet articles which have been suspended from or attached 25 to various parts of the swimming costume and such waterproof devices have also been made which have been fastened on to the belt of the wearer, but I have not prior to my invention, heard of any device for 30 this purpose which is integral with the buckle itself.

Further objects of this invention will be apparent from the specification and drawings in which—

35 Fig. 1 is a perspective view of my improved belt buckle attached to a belt showing the interior construction thereof.

Fig. 2 is a side elevation thereof closed.

40 Fig. 3 is a section along the line 3—3 of Fig. 2.

45 10 denotes the rear plate of a belt buckle having the flanges 10^A and 10^B. This plate has the metal loops 14 of the usual construction to which the ends of the belt are fastened in the ordinary manner. Set within the flanges 10^A and 10^B of the frame of the buckle is a rectangular rubber gasket 11 which is cut out on the interior thereof so as to leave a hollow space. To one end 50 of the plate 10 is joined a hinge 17 to which is attached a hollow box like structure 18,

the edges of which fit the elastic rubber gasket 11 closely, so that when closed, a hollow interior is provided in which may be put cigarettes, mentioned as 19^A, coins 55 12^A, matches 13^A and other objects as desired. The guard 12 acts as a coin retainer; the guard 19 as a holder for the cigarettes. The body 18 has a small protuberance 16^A on the end thereof, which protuberance contacts with the spring 16 when the buckle receptacle is closed. The spring 16 is made with sufficient resiliency so that its head will fit over the protuberance 16^A and will keep the box 18 tightly wedged against the gasket 11. In order to release the receptacle, it is necessary only to exert a slight pressure on the thumbpiece of spring 16 and the box 60 may be readily lifted.

65 I have shown in this embodiment, objects 70 such as matches, coins and cigarettes displayed in the interior of the belt buckle, but it is apparent that other objects such as powder puffs, lipsticks, medicinal articles, etc. may be substituted for these articles, 75 without departing from the spirit of the invention.

It is also apparent that variation may be made in the form of this buckle, such as a change in the metal loops and in the shape 80 of the buckle without departing from the spirit of the invention.

85 It will be seen that I have provided a convenient waterproof receptacle which is integral with the belt buckle and which may be made in a shape not essentially much larger than the usual belt buckle.

Having thus fully described my invention, what I claim is:

90 1. In a belt connector, the combination of a rectangular hollow face plate, a rear plate of substantially the same contour hinged thereto, a rectangular rubber gasket fitting the edges of said rear plate so that the face plate will enclose a water-tight hol- 95 low space when resting on said gasket, loops attached to said rear plate to engage the ends of a belt, and spring means extended in the direction of the length of said face plate for tightly compressing the rear plate 100 and the face plate together.

2. In a belt buckle, a face plate of sub-

stantially rectangular contour and having a flange at right angles thereto and rearwardly thereof so that said face plate forms a receptacle, a hinge at one edge of said face plate, a rear plate attached to said hinge, a rectangular gasket attached to the edges of said rear plate, spring means com-

pressing the face plate against the rear plate and loops attached to said rear plate to which the ends of the belt are fastened. 10
In testimony whereof I hereunto affix my signature.

REGINALD F. LANDRUM.
